UNITED STATES PATENT OFFICE.

EDWARD B. KINGMAN, OF LEOMINSTER, MASSACHUSETTS.

COMB.

SPECIFICATION forming part of Letters Patent No. 691,946, dated January 28, 1902.

Application filed November 2, 1901. Serial No. 80,865. (No model.)

To all whom it may concern:

Be it known that I, EDWARD B. KINGMAN, a citizen of the United States, residing at Leominster, in the county of Worcester and State 5 of Massachusetts, have invented a new and useful Roll-Topped Comb, of which the following is a specification.

This invention relates to a comb which has been especially designed to be stronger and 10 more permanent in its shape than combs now ordinarily employed and which is so shaped that it will more efficiently retain the hair in shape than other forms of combs with which I am familiar.

15 To these ends this invention consists of the comb as an article of manufacture and of the combinations of parts therein, as hereinafter described, and more particularly pointed out in the claims at the end of this specification.

20 In the accompanying drawings, Figure 1 is a rear view of a comb constructed according to my invention. Fig. 2 is a front view of a comb constructed according to my invention, and Fig. 3 is a transverse sectional view of 25 the same.

The ordinary forms of combs employed by ladies for ornamental hair-dressing purposes have been found to be objectionable for several reasons. Ordinary shell, celluloid, or 30 other similar combs are usually comparatively brittle and are easily broken. The cheaper grades of combs, furthermore, are extremely liable to warp and change their shape under the influence of the heat of the 35 head of the wearer, while plain combs of ordinary patterns do not efficiently fasten the hair in the desired shape, the comb frequently working out of place and losing its hold on the shorter hairs.

40 The especial object of my present invention is therefore to provide a comb of a much stronger construction than heretofore employed which will be of a permanent shape and not liable to become warped or twisted 45 and which is so constructed that it will lock itself into place in the hair, so as to efficiently hold the hair of the user in place. To accomplish these results, a comb constructed according to my invention comprises a body 50 portion having ordinary teeth on one edge

and a substantially tubular roll along its other edge, formed by rolling the material around and back upon itself, so that the free edge of the roll is substantially perpendicular to the outer face of the comb along a line intermediate the ends of the teeth, leaving a narrow groove or slot, in which the hair of the user is gripped or fastened. 55

In practice I prefer to slightly sharpen the free edge of the roll, so as to more efficiently 60 engage the hair of the wearer, and in practice combs constructed according to my invention have been employed for back combs, side combs, and of other configurations for use in different styles of hair-dressing. 65

Referring to the accompanying drawings and in detail, a comb constructed according to my invention, as herein illustrated, comprises a curved body portion A, which is slotted along one edge to form the ordinary 70 comb-teeth B. The upper edge of the body portion A is turned or rolled back upon itself to form a substantially tubular roll C, having the lower or free edge D of the roll substantially perpendicular to the body portion 75 of the comb along a line intermediate the ends of the teeth, and the edge D being preferably sharpened or brought to an edge, a narrow slot being left between the body portion of the comb and the free edge D of the roll. 80

In the present instance I have illustrated a comb substantially of the form employed for a "back" comb, so called; but, as before explained, my invention is equally applicable to side combs or to combs used in other places 85 upon the head of the wearer. I do not wish, therefore, to be limited to the construction I have herein shown and described; but

What I do claim, and desire to secure by Letters Patent of the United States, is— 90

1. As an article of manufacture, a comb of the class described, comprising a body portion slotted to form teeth along one edge and having a tubular roll at its opposite edge, the free end of the roll approaching the body portion of the comb at a point intermediate the ends of the teeth, so as to coöperate therewith in gripping or locking the comb in place 95 in the hair.

2. As an article of manufacture, a comb of 100

the class described, comprising a curved body portion A slotted to form comb-teeth B along one edge, and bent back along its opposite edge to form a substantially tubular roll C, 5 the free edge of which is sharpened, as at D, and stands substantially perpendicular to the face of the comb on a line intermediate the ends of the teeth.

In testimony whereof I have hereunto set my hand in the presence of two subscribing witnesses.

EDWARD B. KINGMAN.
